BABY BOTTLE HOLDING DEVICE
Charles D. Crisp, 8510 Spring Circle, Decatur, Ga.
Filed Jan. 26, 1962, Ser. No. 169,017
14 Claims. (Cl. 248—103)

This invention relates to a baby bottle holding device and is more particularly concerned with a bottle holding device for attachment to a baby crib so as to dispose the bottle in an appropriate position for access thereto by a baby within the crib.

In the past many bottle holders have been devised for holding a baby bottle in a predetermined position, relatively inverted so that a child lying on his back may have access to the nipple of the bottle. In most of these devices, the bottle is supported by an arm in a relatively rigid position such that the child cannot move the bottle, in the event the child becomes strangled or no longer desires to have the contents of the bottle. Further, the prior art devices usually include supporting structures having sharp metal edges or springs which may be contacted by the child with sufficient force that they might injure the child. Many of the prior art devices require a finite adjustment of the various elbows, each time the device is employed. Many of the prior art devices will slip from the predetermined positions, especially with vibration such as when the child jumps up and down in the crib.

The present baby bottle holder obviates the difficulties described above and yet is a relatively simple and inexpensive device. Briefly, my baby bottle holder includes, in one embodiment, a pair of opposed supporting brackets adapted to be fastened on the opposite sides of the crib so as to support therebetween an extensible support member. The support member may be rotated, raised or lowered as desired to a plurality of positions, and the width of the support member may be varied to conform to the width of a variety of cribs. The support member, in turn, carries a bottle holder provided with a resilient retaining strap by means of which the bottle is mounted for access thereto by the child. Thus, the bottle may be readily and easily installed in or removed from the bottle holder.

In certain embodiments, the bottle holder is urged by gravity toward the bed of the crib and hence may be pushed away by the child when the child no longer desires the contents of the bottle.

In one embodiment, the bottle holder is held by a support member carried by a single bracket.

Accordingly, it is an object of the present invention to provide a bottle holding device which is inexpensive to manufacture, durable in structure and efficient in operation.

Another object of the present invention is to provide a bottle holding device particularly suited for holding a baby bottle in a relatively inverted position over the head of a crib for access thereto by an infant, the bottle being firmly held in its predetermined position and yet may be readily and easily temporarily urged by the infant away from its predetermined position.

Another object of the present invention is to provide a bottle holding device in which a bottle held thereby may be readily and easily and accurately positioned in a variety of preselected positions.

Another object of the present invention is to provide a bottle holding device which may be quickly and easily adjusted to fit and mount on any one of various cribs.

Another object of the present invention is to provide a bottle holding device which, when holding a baby bottle, will not endanger an infant for which the bottle is held.

Other objects, features and advantages of the present invention will become apparent from the following description when taken in conjunction with the accompany-

2

ing drawings wherein like characters of reference designate corresponding parts throughout the several views and wherein:

FIG. 1 is a plan view of one embodiment of the present bottle holding device disposed on the sides of a crib, the crib being shown in fragmentary form and the bottle supported by the holding device being shown in broken lines therein.

FIG. 2 is an enlarged cross sectional view taken along line 2—2 in FIG. 1, the bottle being deleted from the drawing.

FIG. 3 is a cross sectional view taken along line 3—3 in FIG. 2.

FIG. 4 is an enlarged vertical sectional view taken along line 4—4 in FIG. 2.

FIG. 5 is an enlarged cross sectional view taken along line 5—5 in FIG. 1.

FIG. 6 is a view similar to FIG. 5 but showing the bottle retaining strap disengaged from the bottle holder with the bottle removed from the holder.

FIG. 7 is an enlarged cross sectional view of a detail, showing the bottle holder in a relatively inverted position, the bottle holder being carried by the support members and having its bottle retaining strap unsnapped.

FIG. 8 is a side elevational view on a reduced scale of a second embodiment of the present invention.

FIG. 9 is a plan view of the device shown in FIG. 8.

FIG. 10 is a side elevational view of a third embodiment of the present invention.

FIG. 11 is a plan view of the device shown in FIG. 10.

FIG. 12 is a side elevational view of a fourth embodiment of the present invention.

FIG. 13 is a fragmentary plan view of a portion of the structure shown in FIG. 12.

FIG. 14 is an enlarged fragmentary view of a detail of the device shown in FIG. 12.

FIG. 15 is an enlarged fragmentary view of another detail of the device shown in FIG. 13.

Referring now in detail to the embodiment chosen for the purpose of illustrating the present invention, it being understood that in its broader aspects the present invention is not limited to the exact details herein depicted, in FIG. 1, numeral 20 denotes a crib, cradle or baby bed having sides 21 over the upper edges of which the opposed complementary supporting brackets 22 of the first embodiment are installed.

Since each supporting bracket 22 is identical to the other, it will suffice to describe in detail the construction of but one, as follows: The bracket 21 is a U-shaped member having an outer downwardly extending flange 23, shown in FIG. 4, which is preferably trapezoidal in shape. The shape of the inner flange 24 is the same as the shape of flange 23, the flange 24 being disposed about parallel to flange 23 and in the same horizontal position. The major base, upper edges of flanges 23 and 24 are joined by a web 25, the space between flanges 23 and 24 being sufficient to receive therebetween the upper edge portion of a side 21 when the support bracket 22 is installed over the side 21. The bracket 22 is properly installed, the web 25 comes to rest on the upper surface of side 21 and the flanges 23 and 24 depend downwardly from the web 25 on opposite sides of sides 21.

The inner surface of flange 24 forms a slide supporting member which is provided with an inwardly opening, vertically disposed channel 26, the corners of which are provided with opposed retaining grooves 27 seen in FIG. 3. In the central portion of channel 26, the flange 24 is provided with a plurality of evenly spaced horizontally disposed serrations 28 forming a straight vertically disposed ratchet which cooperates with complementary serrations 29 on a pawl or detent 30.

The pawl 30 is pivotally carried by a slide member or slide plate 31, the serrations 29 being yieldably urged into engagement with serrations 28 by action of a spring (not shown). The slide plate 31 is carried in the channel 26 and has outwardly extending side flanges 32 which ride within the retaining grooves 27. Thus, when the serrations 29 are retracted (away from serrations 28), the slide plate 31 may be freely moved upwardly and downwardly.

Within the slide plate 31 is a second, vertically slideable slide plate 33 which is smaller than slide plate 31 and rides within a vertical channel 34 within the lower and intermediate portions of slide plate 31. The slide plate 33 has flanges 35 which retain the slide plate 34 in place for vertical sliding action within channel 34 and a pawl or detent 36 having serrations 37 for cooperating with vertically spaced serrations 38 in slide plate 31. The ratchet 36 is pivotally carried by slide plate 33 and is urged by spring 39, acting between in a direction such that the serrations 37 engage the serrations 38. Serrations 37 cooperate with serrations 38 in such a manner that the slide plate 33 may be urged upwardly and will remain in the uppermost position attained. On the other hand, pressure on the pawl 36 for movement of the serrations 37 out of engagement with the serration 38 is required if the slide plate 33 is to be moved downwardly.

At the lower end portion of the slide plate 33 is a support member carrying disc 40 pivotally mounted in side-by-side relationship to the slide plate 33 for rotation with respect thereto. The disc 40 has serrations 41 along its periphery, the serrations 41 cooperating with a spring loaded pawl or detent 42 pivotally carried by a ring 43 protruding from slide plate 33 and encompassing disc 40. When pawl 42 is moved away from the disc 40, the disc 40 may be freely rotated. When the pawl 42 is released, it engages the serrations 41 and prevents rotation of the disc 40. If desired, the same type of interengaged serrations may be provided on disc 40 as for the slide plates 31 and 33, in which case the disc 40 may be free to rotate in one direction only.

As seen in FIG. 1, the brackets 22 have discs, such as disc 40, which carry therebetween a pair of extensible support members 50, the support members 50 each including an inner rod 51 telescoping within an outer rod 52. The rods 51 and 52 are respectively secured by their outer ends to the opposed discs 40 at a position radially spaced from the center, such that one support member 50 is diametrically opposed to the other, the two support members 50 extending parallel to each other across the bed or the crib 20.

Slidably carried on the support members 50 is a bottle carrying member, denoted generally by numeral 60. The bottle carrying member or holder 60 includes a concaved or semi-circular bottle cradle or body 61, the sides of which are provided with tangentially arranged parallel side plates 62 which project below the body. The side plates 62 are generally rectangular with the outer ends rounded to eliminate the pointed edges. The side plates 62 are provided with transversely aligned, elongated slots 63 which are disposed axially and are substantially longer than the distance between support members 50, as seen in FIG. 7. The slots 63 are each defined by an upper edge 64 arranged about parallel to the axis of the body 61 and a lower edge 65 which diverges slightly from edge 64, the ends of the two edges being joined by a semi-circular rear edge 66 of substantially the same diameter as rod 52 and a semi-circular forward edge 67, the front edge 67 being of slightly larger diameter than the rear edge.

It will be understood that the bottle carrying member is received on the support members 50 by the support members passing through the aligned slots 63, as illustrated in FIGS. 2 and 7. The loose encompassing of the support members 50 by the plates 62 permits the ready transverse sliding of the bottle carrying member along the support members from one side of the crib 20 to the other. The bottle carrying member 60 is also free to

move longitudinally, with respect to the crib 20, through a limited distance defined by edges 66 and 67.

As seen best in FIGS. 1, 5 and 6, a pair of spaced elastic bands 68 extend radially around the body 61, passing through holes adjacent the side edges of body 61. Thus, normally the upper portion of the elastic bands 68 extends essentially radially across the body 61 as seen in FIG. 6. However, when a bottle 70 is received thereon, the bands 68 are deformed downwardly to conform to the shape of the bottle 70, as seen in FIG. 5, thereby urging the bottle outwardly of body 61.

The outward urging of the bottle 70 is resisted by a strap 71 passing over the outer portion of bottle 70 from one side 62, to which the strap is permanently attached, to the other side 62. The free end of strap 71 contains a button 72 adapted to be engaged in a keyhole slot 73 projecting upwardly from edge 64 at the central portion of the other side plate 62. The outward urging of bottle 70 tends to retain the button 72 locked in place in the small portion of keyhole slot 73, as shown in FIG. 5, unless the button 72 is urged toward the slot 63 and then moved outwardly thereof. Thus, when strapped in body 61, the bottle 70 is resiliently held axially thereof with the nipple end of bottle 70 protruding beyond the end of body 61.

Second Embodiment

Referring now to FIGS. 8 and 9, the second embodiment includes a pair of inverted U-shaped brackets 122, the inner flanges 124 of which are provided with rotatable discs 140. The construction and arrangement of brackets 122 and 22 may be identical if desired, whereby extendable slide plates, such as slide plates 31 and 33, are provided between the rotatable discs 140 and brackets 122.

In the second embodiment, U-shaped bales 141 are provided along the opposed faces of disc 140, the bales 141 being secured to the disc 140 by the end portions of the arms of each bale 140. The webs of bales 140 carry therebetween a continuous resilient support member 150, the central portion of which forms a bottle carrying member 160 for carrying bottle 170.

In more detail, the support member 150 is a continuous extensible resilient belt which has a pair of slideable clamps 162 which encompass the opposed flights of member 150. In operation, the brackets 122 are placed over the sides of a crib so as to hold the belt or member 150 in a stretched condition. A bottle 170 is placed between the central portion of the opposed flights of belt 150 and the clamps 162 are moved adjacent the opposite sides of the bottle 170, as shown in FIGS. 8 and 9. Thus, the bottle is supported in place and may be rotated about a transverse axis upon rotation of disc 140. The bottle 170 may be shifted transversely, relocating the clamps 162.

Third Embodiment

The third embodiment, shown in FIGS. 10 and 11, includes a pair of opposed brackets 222, similar to brackets 122, a pair of opposed discs 240 having bales 241 similar to discs 140 and bales 141. The discs 240 are rotatably carried on brackets 222 while bales 241 carry therebetween a flat, resilient belt-like support member 250, the ends of which pass through the bales 240 and are adjustably fixed against intermediate portions of the support member 250 by clamps 262.

Secured to the central portion of support 250 by stitching or the like is a strap 271, the free end of which is provided with a button or clasp 272. The button 272 is adapted to pass through a button hole in the support member 250 so as to encompass one-half of a bottle 270, the other half of which is resiliently held by the central portion 260 of the support member 250.

The bottle 270 may be moved transversely by adjusting clamps 262 and may be rotated by rotating discs 240.

Fourth Embodiment

The fourth embodiment, shown in FIGS. 12 through 15, includes a U-shaped bracket 322 having an upper flange 323 and a lower flange 324 connected together by a web 325, in turn, is provided with a pair of spaced vertically aligned clamps 326 which are adapted to extend around a spoke or post 321 of one side of a crib 320, the clamps 326 being pivotally connected by one side to web 325 so that wing nuts 327 which fit onto the ends of screws 328 which project from the other side of web 325 through the clamps 326 secure the clamps 326 in place.

Between the flanges 323 and 324 is a slide supporting member 331 which in this particular embodiment is a circular standard. A slide or collar 332 is mounted on standard 331 and carries a detent 336 adapted to fit into any one of a plurality of vertically spaced recesses 338 in standard 331, the detent being spring loaded so as to be disengageable from any recess 338 when it is desired to shift the location of collar 332. The upper peripheral edge of collar 332 is serrated at numeral 341 and receives the serrations of a second sleeve or collar 340 on standard 331. Collar 340 has a bushing 342 surrounding standard 331 and is freely rotatable and slidable on standard 331.

Extending from the collar 340 is a support member 350. Support member 350 is a cantilever arm which is secured by one end to collar 340 and has top and bottom edges 351 and 352 which taper outwardly to a narrow outer end. On the outer end is an outwardly and downwardly extending yoke 353 having, between its arms, a pair of spaced parallel rods 354 adapted to receive a bottle holder (not shown) in the manner in which the bottle carrying member of holder 60 is carried by rods 50 in FIG. 7.

It will be understood that by raising or lowering of the collar 332, the bottle (not shown) carried by the bottle holder (not shown) on yoke 353 may be raised or lowered. Also, by pivoting arm 350, the relative location of the bottle (not shown) may be varied.

From the foregoing description, it will be seen that each of the embodiments here disclosed will dispose a baby bottle in a relatively inverted position over a child in a crib, the bottle being readily and easily removed or installed in the holding device.

With reference to the first embodiment, the bottle 70 may be raised or lowered by manipulation of slide plates 31 and 33 and may be rotated about a transverse axis to any predetermined angle by manipulation of disc 40. The bottle 70 may also be moved transversely by sliding the holder 60 along the support member 50. The bottle 70 may be pushed away by the child, whereby the holder 60 shifts within the limits of slots 63 and returns by gravity to its original position.

The same type of rotation of the bottle 170 and 270 may be achieved with the second and third embodiments by rotation of discs 140 or 240 while the transverse shifting of the bottle 170 or 270 is accomplished by manipulation of the belts or support members 150 or 250.

In each embodiment, the bottle 70, 170 or 270 is resiliently carried and hence will move slightly in its held position, as the child pushes on the bottle.

It will be obvious to those skilled in the art that many variations may be made in the embodiments here chosen for the purpose of illustrating the present invention without departing from the scope thereof as defined by the appended claims.

I claim:

1. In a bottle holder of the type wherein bracket means are adapted to be supported by the side of a crib, the combination therewith of a rotatable member carried by said bracket means, a support member carried by said rotatable member for rotation therewith, and a resilient bottle holder carried by said support member, said bottle

holder including a pair of opposed flat, resilient straps for extending around opposite sides of a bottle to support the same in said bottle holder.

2. In a bottle holder of the type wherein bracket means are adapted to be supported by the side of a crib, the combination therewith of a rotatable member carried by said bracket means, a support member carried by said rotatable member for rotation therewith, and a resilient bottle holder carried by said support member, said bottle holder including a pair of opposed flat, resilient straps for extending around opposite sides of a bottle to support the same in said bottle holder, said support member including a pair of spaced rods, said bottle holder being slidably received on said rods.
3. In a bottle holder of the type wherein bracket means are adapted to be supported by the side of a crib, the combination therewith of a rotatable member carried by said bracket means, a support member carried by said rotatable member for rotation therewith, and a resilient bottle holder carried by said support member, said bottle holder including a pair of opposed flat, resilient straps for extending around opposite sides of a bottle to support the same in said bottle holder, and ratchet means for yieldably preventing rotation of said rotatable member.
4. In a bottle holder of the type wherein bracket means are adapted to be supported by the side of a crib, the combination therewith of a rotatable member carried by said bracket means, a support member carried by said rotatable member for rotation therewith, and a resilient bottle holder carried by said support member, said bottle holder including a pair of opposed flat, resilient straps for extending around opposite sides of a bottle to support the same in said bottle holder, and ratchet means for yieldably preventing rotation of said rotatable member.
5. In a bottle holder of the type wherein a pair of opposed brackets are adapted to be supported by the sides of a crib, the combination therewith of a pair of rotatable members carried by said brackets, support members carried between said rotatable members for rotation therewith, and a resilient bottle holder carried by said support members.
6. In a bottle holder of the type wherein a pair of opposed brackets are adapted to be supported by the sides of a crib, the combination therewith of extensible means carried by said brackets, a pair of rotatable members carried by said extensible means, support members carried between said rotatable members for rotation therewith, and a resilient bottle holder carried by said support members.
7. In a bottle holder of the type wherein a pair of opposed brackets are adapted to be supported by the sides of a crib, the combination therewith of extensible means carried by said brackets, a pair of rotatable members carried by said extensible means, a support member carried between said rotatable members for rotation therewith, and a resilient bottle holder carried by said support member, said bottle holder including a pair of opposed flat, resilient straps for extending around opposite sides of a bottle to support the same in said bottle holder.
8. In a bottle holder of the type wherein a pair of opposed brackets are adapted to be supported by the sides of a crib, the combination therewith of extensible means carried by said brackets, a pair of rotatable members carried by said extensible means, a support member carried between said rotatable members for rotation therewith, and a resilient bottle holder carried by said support members, said bottle holder including a pair of opposed flat, resilient straps for extending around opposite sides of a bottle to support the same in said bottle holder, and a bottle cradle supporting said straps, said bottle cradle being slidably carried on said support member for movement between said rotatable members.

9. In a bottle holder of the type wherein a pair of opposed brackets are adapted to be supported by the sides of a crib, the combination therewith of extensible means carried by said brackets, a pair of rotatable members carried by said extensible means, support members carried between said rotatable members for rotation therewith, and a resilient bottle holder carried by said support member, said bottle holder including a pair of opposed flat, resilient straps for extending around opposite sides of a bottle to support the same in said bottle holder, and a bottle cradle supporting said straps, said bottle cradle being provided with a slot through which said support member projects, said slot being wider and substantially longer than the thickness and width of said support member such that said bottle holder may slide on said support member between said rotatable members and may be moved radially thereof.

10. In a bottle holder of the type wherein a pair of opposed brackets are adapted to be supported by the sides of a crib, the combination therewith of extensible means carried by said brackets, a pair of rotatable members carried by said extensible means, support member carried between said rotatable members for rotation therewith, and a resilient bottle holder carried by said support member, said bottle holder including a pair of opposed flat, resilient straps for extending around opposite sides of a bottle to support the same in said bottle holder, a bottle cradle supporting said straps, said bottle cradle being provided with a slot through which said support member projects, said slot being wider and substantially longer than the thickness and width of said support member such that said bottle holder may slide on said support member between said rotatable members and may be moved radially thereof, said support member including a pair of telescoping rods arranged parallel to each other, said extensible means including slide plates carried by said brackets and detent members for positioning said slide plates in preselected positions.

11. In a bottle holder of the type wherein bracket means are adapted to be mounted on a crib, the combination therewith of a rotatable member carried by said bracket means, detent means for preventing rotation of said rotatable member, a support member carried by said rotatable member, a bottle holder carried by said sup-

5

port member for rotation movement in a horizontal plane upon rotation of said rotatable member, said bottle holder including yieldable means for supporting a bottle, said yieldable means permitting said bottle to be moved as the same is held thereby, said yieldable means resisting said movement such that when said bottle is released it will return to substantially its original position.

12. In a bottle holder of the type wherein bracket means are adapted to be mounted on a crib, the combination therewith of a rotatable member carried by said bracket means, detent means for preventing rotation of said rotatable member, a support member carried by said rotatable member, a bottle holder carried by said support member for rotation movement in a horizontal plane upon rotation of said rotatable member, said bottle holder including yieldable means for supporting a bottle, said yieldable means permitting said bottle to be moved as the same is held thereby, said yieldable means resisting said movement such that when said bottle is released it will return to substantially its original position, and slide means interposed between said support member and said bracket means and a second detent means for positioning said slide means in any one of a plurality of positions for varying the vertical position of said support means with respect to said bracket means.

13. The structure defined in claim 12 wherein said yieldable means includes a bottle cradle movable transversely of said support member and urged by gravity toward the bed of said crib.

14. The structure defined in claim 13 wherein said yieldable means also includes a flat resilient strap carried by said bottle cradle and means for releasably securing a portion of said strap to said cradle for holding a bottle therebetween.
